UNITED STATES PATENT OFFICE.

EDWARD E. PINKERTON, OF CHICAGO, ILLINOIS.

BOX.

Application filed June 29, 1923. Serial No. 648,414.

To all whom it may concern:

Be it known that I, EDWARD E. PINKERTON, a citizen of the United States, and a resident of the city of Chicago, county of Cook, and State of Illinois, have invented certain new and useful Improvements in Boxes, of which the following is a specification.

My invention relates to new and useful improvements in boxes, and more particularly to folded cardboard boxes, and has for an object to provide such boxes with reinforced or multiple walls and with lace means extending from said walls and providing an artistic superposed lace effect, all the parts of said box being stamped from a sheet of material to form a single integral pattern or blank which is folded into the required shape.

Other objects will appear hereinafter.

The invention consists in the combinations and arrangements of parts hereinafter described and claimed.

The invention will be best understood by reference to the accompanying drawings forming a part of this specification, and in which,

Fig. 1 is a view of the integral pattern or blank stamped out from a sheet of material; Fig. 2 is a top view of the folded box with the cover in open position;

Fig. 3 is an enlarged vertical section taken on line 3—3 of Fig. 2; and

Fig. 4 is a vertical cross section taken on line 4—4 of Fig. 3.

In the drawings, I have shown one form of my invention which is produced by stamping a single and integral blank or pattern from a sheet of suitable material, such as cardboard or the like, to form the required box blank as shown in Fig. 1. This blank comprises a main portion (M) forming the exterior of the box, and a reinforcing portion (R) forming the inner part of the box, when the parts are folded along the dotted lines shown in Fig. 1 and the fastening means are arranged in position.

The main portion, or exterior portion (M) comprises a bottom 11 with two side walls 12 and 13 thereon, a top member 14 extending from the side wall 12 and having a flap 15 to engage in slot 15' provided in side wall 13. Two end walls 16 extend from the bottom 11 and have their end parts 17 doubled over inwardly thereon, and are provided with short side flaps 18 which extend

along the inside of the side walls 12 and 13 in the finished box. A lace member 19 is cut out from each portion 17, having its edge indented or trimmed in the manner of lace, and extends inwardly from the upper doubled edge of each end wall, and corner flaps 20, which are cut from the sides of said ends walls and flaps, extend from the side walls and are tucked in between the doubled portions of said end walls.

The inner or reinforcing portions (R) of the box comprises a bottom member 21 and two side members 22 and 23 extending therefrom, the member 23 extending from the main side wall 13 and the member 22 containing a narrow strip or flap 22' which is bent over outwardly and is fastened to the upper part of said wall 12, as by the use of adhesive material provided on said strip. Two end members 26 extend from said member 21 and have tongues 27 cut out therefrom which are extended inwardly through slots 28 in wall portions 17 when said end members 26 are placed on the inside of portions 17 of the wall member 16. Lace members 29, which have their edges indented or trimmed similar to the lace members 19, are provided on the outer ends of members 26 and are extended inwardly into the box, the lace members 19 being folded thereover and therewith forming superposed or multiple layers of lace means on the box, thus providing the much desired and artistic doubled or multiple lace effect, without the necessity of pasting additional lace means in the box as is the case in the usual present construction, thereby lessening the amount of work involved to make the box and therefore lessening its cost of production.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A box consisting of a single sheet of material and comprising a main portion with an outer end wall doubled over inwardly, a lace member cut out and extend-

ing from said end wall, a reinforcing portion bent inward from said main portion and having an end member inside of said end wall, and lace means on said end member extended beneath said lace member to form a superposed lace effect.

2. A box consisting of a single blank of material and comprising a main portion providing outer end walls having the upper 10 parts doubled over inwardly, a lace member cut out and extending inwardly from the bent top part of each end wall, a reinforcing portion extending from said main portion and folded inward thereof and having 15 end members placed at the inner sides of said end walls, and lace members bent inwardly from said end members and folded onto the first said lace member forming superposed lace means therewith.

20 3. A box having its parts integral and comprising a main outer portion and an inner reinforcing portion, said main portion containing bottom and side walls and a lid extending from one of said side walls, said 25 reinforcing portion extending from the other side wall and forming inner bottom, side and end members, lace members extending inwardly from said end members, end walls on said main portion doubled over inwardly, corner flaps extending 30 from said side walls and tucked between the doubled parts of said end walls, and lace members cut out from said end walls, and lace members cut out from

said doubled end walls and folded inward being doubled over the first said lace members with the lace edges slightly above the 35 lace edges of the first said lace members to form a multiple lace effect.

4. A box consisting of a single blank of material and comprising a main outer portion and an inner reinforcing portion, said 40 main portion containing bottom and side walls and a lid extending from one of said side walls and having a flap on its outer end, said reinforcing portion extending from the other side wall and forming a slot there- 45 with for receiving said flap, said reinforcing portion also forming inner bottom, side and end members, tongues on said end members, lace members extending inwardly from said end members, end walls on said main portion doubled over inwardly and having slots to receive said tongues, side flaps on 50 said end walls directed under the side walls of the main portion, corner flaps extending from said side walls and tucked between the doubled parts of said end walls, and lace members cut out from 55 said end walls and folded inward over the first said lace members to expose the lace edges there- of and form a superposed lace effect.

In testimony whereof I have signed my name to this specification,

EDWARD E. PINKERTON.
